US00D621520S

(12) **United States Design Patent**
Talmer et al.

(10) **Patent No.:** **US D621,520 S**
(45) **Date of Patent:** ** *Aug. 10, 2010

(54) **CUVETTE**

(75) Inventors: **Mark Talmer**, Pepperell, MA (US);
Paul C. Dahlstrom, Hollis, NH (US)

(73) Assignee: **Biokit, S.A.**, Barcelona (ES)

(*) Notice: This patent is subject to a terminal disclaimer.

(**) Term: **14 Years**

(21) Appl. No.: **29/327,915**

(22) Filed: **Nov. 14, 2008**
